UNITED STATES PATENT OFFICE.

JAMES H. McCOOL, OF ELLSWORTH, KANSAS.

ATTACHMENT FOR POOL-TABLES.

1,386,578.

Specification of Letters Patent.

Patented Aug. 2, 1921.

Application filed November 9, 1920. Serial No. 422,866.

To all whom it may concern:

Be it known that I, JAMES H. McCool, a citizen of the United States, residing at Ellsworth, in the county of Ellsworth and State 5 of Kansas, have invented new and useful Improvements in Attachments for Pool-Tables, of which the following is a specification.

My present invention has reference to improvements in pool tables, and more particularly to a pool table which is provided with tracks common to the ball receiving pockets whereby the balls may be delivered into racks at one end of the table.

15 The primary object is the provision of means for attaching the pockets to the table so that the balls will be positively directed to the tracks.

A further object is to produce a means for 20 securing the pockets to the table and for supporting the rails which constitute the tracks.

A still further object is the production of a pool table attachment for this purpose which shall be of an extremely simple construction, cheaply manufactured, readily attached to any ordinary construction of pool tables, and thoroughly efficient for the purpose for which it is devised.

The foregoing, and other objects which 30 will appear as the nature of the invention is better understood, may be accomplished by a construction, combination and operative arrangement of parts, such as is disclosed by the drawings which accompany and 35 which form part of this application.

In the drawings:—

Figure 1 is a fragmentary side elevation of a pool table illustrating the improvement.

40 Fig. 2 is a sectional view on the line 2—2 of Fig. 1.

Fig. 3 is a fragmentary plan view of the pool table, looking toward the pocket.

In the drawings, the numeral 1 broadly indicates an ordinary construction of pool 45 tables. This table is provided with the usual side and corner pockets. The top rail 2 of the table, at the cut-away portion thereof for

the pockets has secured thereto a flat arched plate 3 disposed at the outer rounded portion of the pocket. The rounded plates 3 have 50 their securing means 4 passing through the straight extensions at the ends thereof, and the said securing means also support on the table depending frames 5. Each of the frames is of a substantially rectangular formation 55 and have their parallel side members connected to rods 6 which provide the rails of a track 7 for the playing balls.

The pocket is indicated by the numeral 8 and is in the nature of a member woven from 60 leather strips, but the said pocket is open at both its top and bottom, the said top having its outer edge secured in the usual manner to the top rail 2 by the iron 3. The iron 3 also supports a fabric, such as a leather reinforcing member 9 at the top of the pocket.

With my construction, it will be seen that the pocket is not provided with a bottom, that the ordinary pocket iron is employed, and that the yokes effectively hold the pocket 70 in spread condition as well as provide supports for the rails of the track. It is thought that the foregoing description, when taken in connection with the drawings will fully set forth the construction and advantages of 75 the improvement to those skilled in the art to which such inventions relate, but it is thought necessary to add that I am entitled to make all such changes therefrom as fall within the scope of what is claimed. 80

Having described the invention, I claim:—

In combination with a pool table having an inclined track for directing the balls from the ball receiving pockets, of a woven pocket having both its top and bottom open, a flat 85 arched member securing the top of the pocket to the top of the table, frames arranged in the pocket, connected to the table by the means which secures the arched member thereto, and said frames retaining the 90 pocket in spread condition and supporting the track.

In testimony whereof I affix my signature.

JAMES H. McCOOL.
